UNITED STATES PATENT OFFICE.

WILLIAM C. WETHERHOLT, OF HUNTINGTON, WEST VIRGINIA.

DESIGN FOR A KITCHEN-CABINET.

SPECIFICATION forming part of Design No. 24,366, dated June 4, 1895.

Application filed April 18, 1895. Serial No. 546,272. Term of patent 3½ years.

To all whom it may concern:

Be it known that I, WILLIAM C. WETHERHOLT, a citizen of the United States of America, residing at Huntington, in the county of

5 Cabell and State of West Virginia, have invented and produced a new and original Design for Kitchen-Cabinets, of which the following is a specification, reference being had to the accompanying drawings, and to letters 10 of reference marked thereon, which form a part thereof.

This design relates to kitchen cabinets, and embodies a cabinet having a paneled front above which is a rearwardly curved top with 15 sliding cover and compartments above said top.

In the accompanying drawings, Figure 1 is 20 a front elevation of the cabinet, and Fig. 2 is a perspective view showing the top raised and the drawers and door partially open.

The front edge of the side pieces A A of the cabinet are curved rearwardly near their upper ends as shown and above the termination of the curved portion extend upwardly 25 and are provided on their outer sides with suitable beading a. There are vertical partitions and transverse strips between the side pieces forming a series of spaces for the reception of drawers, the front of the end drawers 30 a' at the upper part of the cabinet being square while the center drawers a² are oblong. Directly below the curved portion of the side pieces is a transverse strip b against which the edge of a roll-top B bears when lowered, 35 said roll-top conforming to the curved portion of the front edges of the side pieces.

The front of the lower part of the cabinet

is made up of a number of panels, one of the panels forming the front of a drawer while another forms a door to a compartment or 40 cupboard.

The drawers hereinbefore referred to have centrally disposed knobs, and a knob is placed at one side of the door.

By reference to the drawings it will be seen 45 that the side pieces recede and the depth of the upper part of the cabinet is less than the depth of the lower part.

The lower end of the front of the cabinet is made up of a transverse board or strip the 50 lower edge of which is cut away as shown so that the ends thereof with the sides of the cabinet form supporting feet.

The leading features of my design consist of the side pieces having their front edges 55 curved, drawers located between the side pieces above their curved portions, a roll-top below the upper drawers and conforming to the curved portions of the side pieces, and a body below the roll-top comprising a paneled 60 front one of the panels being the front of a drawer and another the door of a cupboard, substantially as hereinbefore set forth.

Having thus described and illustrated my invention, I claim—

The design for a kitchen cabinet herein shown.

In testimony whereof I affix my signature in presence of two witnesses.

WM. C. WETHERHOLT.
